K. MEYER-GAUS
YARN REEL, MORE PARTICULARLY FOR THE WINDING
OF FRESHLY SPUN ARTIFICIAL SILK
Filed Oct. 1, 1926

UNITED STATES PATENT OFFICE.

KARL MEYER-GAUS, OF BARMEN, GERMANY, ASSIGNOR TO AMERICAN BEMBERG CORPORATION, OF NEW YORK, N. Y.

YARN REEL, MORE PARTICULARLY FOR THE WINDING OF FRESHLY-SPUN ARTIFICIAL SILK.

Application filed October 1, 1926, Serial No 138 962, and in Germany October 3, 1925.

Freshly spun artificial silk has hitherto been wound on to bobbins, rollers and reels. The reels have the great advantage of delivering the artificial silk directly in the form of skeins, which is an important advantage for the further treatment of the silk. Unfortunately reels are subject to a serious objection. The silk that is wound is wet and highly tensioned so that it cannot be stripped off as a hank without damaging. Reels have therefore been made which permit of a reduction of their periphery for the purpose of enabling the relaxed skein to be subsequently removed. The reduction in the circumference of the reel has been obtained by cross beams movable in various ways.

One construction is such that one or more cross beams are provided with pivoted spokes, so that a displacement of the cross beams parallel to the longitudinal axis is made possible. In use the movable spokes are fixed perpendicular to the axis by means of a spring or the like. This reel however still exhibits the disadvantage of causing damage to the silk. This arises from the fact that the silk is under strong tension and therefore, when the spokes of the cross bars are folded back, is initially always in contact, and is thus rubbed sideways.

Another construction obviates this lateral friction. In this case the circumference of the reel is diminished by one or more cross bars being so arranged as to be rotatable about the axis in the peripheral direction of the reel, and, in use, to be fixed in their position by a spring for example. Even in the case of this construction, however, no instantaneous relaxation of the silk is obtained when collapsing. Here again friction occurs which acts indeed in the longitudinal direction of the silk but may still also lead to breakage of the threads.

A collapsing of the reel without rubbing the silk is obtained by another construction. In the case of the latter, one or more cross beams are movable in a radial direction along their stationary spokes, struts pivotally connected with the cross beams being so arranged as to be slidable by means of bushes on the shaft. Rails or resilient snap devices hold the cross beams in the struttet position. This construction obviates all friction and damage to the artificial silk during collapsing and

thus completely fulfils the requirements from this point of view.

Nevertheless this construction of the reel could not be introduced into the cuprammonium silk industry. In this industry filaments saturated with sulphuric acid and copper sulphate solution have to be wound, as a result of which the reel becomes unusable within a short time, whether it is made of wood, which quickly rots, or whether it is made of metal, in which case at least the sensitive parts, such as springs and joints, rapidly become corroded. The employment of acid proof steel, has not come into question, for these materials are very difficult to work. Thus for example the fixing devices make the construction described, which moreover is already not simple, very complicated, and thoroughly unsuitable for being made from acid-proof steel.

Now the applicant has discovered a different construction of reel, which combines the advantages of the last mentioned with simplicity, so that the reel can advantageously be made of acid proof steel plates. One or more cross bars are in this case slidable in a radial direction along the spokes and thus relax the tension of the skein of silk without any rubbing. The cross bars are pivotally secured with struts to the shaft itself. The latter is slidably fitted into a box-shaped frame, which is formed from the stationary spokes and cross bars. The bushes slidable along a stationary shaft are thus omitted in this construction. In the struttet position the shaft touches, on the strut joints, the two spiders, and in this position can be held fast in the simplest manner by a bar.

The method of constructing the apparatus forming the subject-matter of the present invention may be seen from the accompanying drawings:

Fig. 1 and Fig. 5 show one constructional form of the reel in a struttet position in cross section and longitudinal section respectively.

Fig. 2 and Fig. 6 show the same reel in a collapsed condition.

Figs. 3, 4, 7 and 8 show a modification.

The cross bars *a*, *b*, *d* and *e* are connected with the spiders *h* to form a rigid box-shaped frame. In this frame a shaft *i* of the reel is so arranged so as to be slidable in a longi-

tudinal direction through the spiders *h*. With the shaft *i* are pivotally connected the two cross bars *c* and *f* by means of the four stays *g*, so that by *c*, *i*, *f* and the four stays *g* 5 *slidable parallelograms* are formed. The pivotal connections of the stays *g* to the shaft *i* and the cross bars *c* are denoted by *m* and *n* respectively. In the two spiders *h* are guided the two cross bars *c* and *f* in such a 10 way that movements in the longitudinal direction are not possible, while movements in a radial direction are possible. This guide may be of any desired form. To show what may be done lugs *r* are provided on the bars 15 *c* and *f*.

Now if the shaft *i* and the box-shaped frame are displaced relatively to one another the pivoted stays *g* pull the two cross bars *c* and *f* radially together (Fig. 2) or press 20 them apart (Fig. 1). Owing to the purely radial movement of the cross bars and the avoidance of any lateral movement, no sort of dragging occurs in the reeled silk skeins. In the struttet position the shaft is held fast 25 with the stays by a lock *K*, which can rotate on the pivot *l* on the shaft *i*.

The cross bars may also be held fast in the struttet position in another way, for example by the stays in this position not being 30 exactly radial in direction, but deflected somewhat beyond the dead centre position, until the joint mounted on the pivot comes into contact with the box-shaped frame formed by the fixed cross bars and spokes. 35 The holding is obtained by the tension in the silk; in this way no fixing device is necessary. By this means the manufacture is specially simplified and the employment of acid proof steel facilitated.

40 This form of the reel is illustrated in Figs. 3 and 7 and 4 and 8. In the displayed or struttet end position two opposite stays *g* do not form a straight line, but are bent a little away beyond the straight line *k* (Fig. 7), 45 whereby an undesired dropping of the cross bars *c* and *f* back into the collapsed end position (Figs. 4 and 8) during the reeling of the artificial silk is obviated, as the tension in the reeled artificial silk makes a buckling 50 of the stays *g* impossible. When collapsing,

the stays *g*, against the pull of the artificial silk, are bent beyond the straight line *k*, whereupon the reel collapses.

I claim:

1. A reel comprising spiders, cross bars 55 fixed to said spiders, cross bars mounted in said spiders and shiftable radially only therein, a shaft axially movable in said spiders, and toggle joints intermediate said shiftable cross bars and shaft. 60

2. A reel comprising spiders, cross bars fixed to said spiders, cross bars mounted in said spiders and shiftable radially only therein, a shaft axially movable in said spiders, toggle joints intermediate said shiftable cross bars and shaft, and means to arrest 65 said shaft in the position in which the toggle joints are stretched.

3. A reel comprising in combination a shaft, a pair of parallel spiders non-rotatably mounted on said shaft, a plurality of parallel cross-bars mounted in said spiders, one of said cross-bars being movable radially only in said spiders, parallel links pivoted at their inner ends to said shaft and 70 at their outer ends to said movable cross-bar, said shaft being arranged to move in one direction to draw said movable cross-bar radially inward and in the opposite direction to move said movable cross-bar radially outward, substantially as described. 75

4. A reel comprising in combination, a shaft, a pair of spiders non-rotatably mounted on said shaft, cross-bars mounted in said spiders to form a reel, two opposite cross-bars being movable radially only in said spiders, two pairs of parallel links connected to said movable cross-bars and to said shaft to form a toggle mechanism for moving said movable cross-bars radially, said shaft being 80 movable longitudinally in one direction to bring the links into a position substantially at a right angle to the shaft to hold said cross-bars in outermost position and being movable in the opposite direction to draw 85 said cross-bars inwardly, substantially as described. 90

In testimony whereof I have affixed my signature.

KARL MEYER-GAUS.
